UNITED STATES PATENT OFFICE.

EDWIN J. WHEELER, OF BROOKLYN, NEW YORK.

CIRCULATOR FOR STEAM-BOILERS.

No. 874,470.

Specification of Letters Patent.

Patented Dec. 24, 1907.

Application filed March 26, 1907, Serial No. 364,591.

To all whom it may concern:

Be it known that I, EDWIN J. WHEELER, a citizen of the United States, residing in Brooklyn, Kings county, State of New York, have invented certain new and useful Improvements in Circulators for Steam-Boilers, of which the following is such a full, clear, and exact description as will enable any one skilled in the art to which it appertains to make and use the same, reference being had to the accompanying drawings, forming part of this specification.

My invention relates to a mechanical circulator which is adapted to be attached to steam boilers or generators in which the circulation of the water is sluggish or poor.

The principal objects of the invention are to provide a simple form of mechanical circulator which is at the same time efficient in producing a good circulation of the water with a positive action, thereby keeping the boiler free from sediment or scale and maintaining the same heated throughout uniformly, and thus serving to keep the boiler free from leaks and thereby prolonging the life of the same.

With these and other objects in view, my invention consists in the various novel and peculiar arrangements and combinations of the several different parts of the apparatus, all as hereinafter fully set forth and then pointed out in the claims.

I have illustrated a type of my invention in the accompanying drawings, wherein; Figure 1 is a central horizontal sectional view of my improved mechanical circulator shown as mounted upon a detachable man-hole cover of a steam boiler. Fig. 2 is a view of the inner end of the agitator mounted upon the man-hole cover, which is shown as detached. Fig. 3 is an exterior view of the parts shown in Fig. 1, with the wall of the boiler omitted and with one edge of the man-hole cover broken away, likewise the ends of the clamping yokes.

Referring to the drawings in which like numbers of reference designate like parts throughout, 1 indicates the wall at the end of a steam boiler or generator and which wall is provided with a man-hole 2 having a removable cover 3 which is provided with posts or bolts 4 fixed therein and having their outer ends provided with screw threads 5 on which fit screw threaded nuts 6, the outer ends of the bolts or posts 4 extending loosely through

the perforation 7 in the clamping yoke 8, which is a heavy U-shaped part with its ends projecting inwardly and is adapted to span the man-hole 2 and by means of which and the bolts and the nuts, the man-hole cover 3 is securely clamped and held in place, in a manner well-known.

Through a perforation 9 in the man-hole extends a rotary shaft 10 which is provided upon its inner end with an agitator having a set of wings or blades 11 which are shaped something like the blades of a propeller and are attached at an angle which is most effective for agitating the water. Between the agitator 11 on the inner end of the shaft and the adjacent side of the wall, or the man-hole cover 3, there is fixed on the shaft 10 a member or collar 12 which is made fast thereon by a set screw 13. At the outer end of the opening 9 in the man-hole cover 3 is arranged a stuffing box or packing 14 for the shaft, to make a steam tight joint. Upon the outer face of the man-hole cover 3 is secured a fixed plate or bearing 15 which is suitably bent and has its respective ends made fast to the cover 3, by means of rivets 16. This plate or bracket 15 is provided with a perforation 17, through which the rotary shaft 10 passes, and the shaft is provided at its outer end with a band-wheel or pulley 18, for driving the shaft.

A portion of the shaft in the vicinity of the fixed plate 15, is provided with an external screw-thread 19, and upon this thread, toward the inner side of the fixed plate, works an adjustable bearing-plate or nut 20, having an interior screw-thread fitting the thread 19 on the shaft. The periphery of this bearing plate or nut 20, is provided with small holes 21 within which the end of a rod may be inserted to turn the nut on the thread on the shaft, in one direction or the other, to adjust it toward the fixed plate 15, or away from the same as the case may be. A nut 22 similar to the nut 20, is mounted on the screw-thread 19, to the inner side thereof and serves as a jam-nut for the nut or plate 20.

To the exterior of the fixed plate 15 there is mounted upon the screw-thread 19 on the shaft, a pair of nuts 20' and 22', similar to the nuts 20 and 22, just described, and which operate in the same way. It will be understood, that the nuts 20, 22, and 20', 22' are to be adjusted relatively to the fixed bearing plate 15, in such a manner, to take up all of

the end-thrust received by the shaft 10 of the agitator in its operation, there being considerable such thrust thrown upon the shaft by the pressure in the boiler as well as the operation of the agitated blades themselves. This will prevent the outwardly directed end-thrust on the shaft 10, from pressing the fixed collar 12 against the inner face of the man-hole, thereby avoiding a great amount of friction, which would otherwise be produced, and transferring same to the exterior part 15, which may be always kept well oiled and properly adjusted, it being easily accessible from the exterior of the boiler.

15 It will be understood that my improved apparatus may be applied to Scotch-marine boilers or any other type of boilers and that it may be located in any desired part of the same, either directly on the wall of the boiler 20 itself or upon the detachable man-hole cover or plate which latter method I have shown as being the preferred one, for in such case the apparatus is placed in operative position without cutting or in any way injuring the 25 boiler proper. Of course, the drive shaft 10 may be driven by a motor or in any suitable well-known manner. The different parts of the apparatus may be made out of suitable metal or any other desired well-known material and the various different parts may be modified or changed without departing from the spirit of the invention.

The method herewith shown of agitating or circulating the water by this mechanical means is a practical and positive method and serves to increase the steaming quality of the boiler and which, of course, results in economizing the amount of coal used as well as protecting the boiler against scale and 40 keeping it free from sediment. The agitator may be placed in any desired part of the boiler and particularly at a place where the water would otherwise remain dead or have the least circulation. Of course, any well-known form of agitator or stirrer may be 45 used in place of the ordinary propeller-like device which I have herewith shown and the

invention will be found to be particularly applicable to marine boilers.

Having thus described my invention what 50 I claim and desire to secure by Letters Patent is:—

1. The combination of a boiler provided with a man-hole having a removable cover, means for securely locking the cover in place, 55 a rotary shaft 10 extending through said man-hole cover and having a bearing thereon, an agitator mounted upon the inner part of said shaft so as to be maintained within the body of water within the boiler.

2. The combination of a boiler provided with a man-hole having a removable cover, means for securely locking the cover in place, 60 a rotary shaft 10 extending through said man-hole cover and having a bearing thereon, an agitator mounted upon the inner part of said shaft so as to be maintained within the body of water within the boiler, a collar 12 mounted upon the inner part of said shaft, and an adjustable bearing for the shaft located upon the exterior of the said man-hole cover.

3. The combination of a boiler provided with a man-hole having a removable cover, 75 means for securely locking the cover in place, a rotary shaft 10 extending through said man-hole cover and having a bearing thereon, an agitator mounted upon the inner part of said shaft so as to be maintained within the body of water within the boiler, a collar 12 mounted upon the inner part of said shaft, a bracket 15 secured upon the exterior of said cover and provided with a perforation 17 through which said shaft passes, nuts 20 and 22 mounted upon said shaft 10 upon 80 opposite sides of the bracket 15, for receiving the end thrust of the shaft.

In testimony whereof, I have hereunto set my hand in the presence of the two subscribing witnesses.

EDWIN J. WHEELER.
